UNITED STATES PATENT OFFICE.

OTTO WENTZEL, OF JERSEY CITY, NEW JERSEY, ASSIGNOR OF ONE-HALF
TO EMIL KOHLER, OF NEWARK, NEW JERSEY.

SAFETY DEVICE FOR PIN-TONGUES.

SPECIFICATION forming part of Letters Patent No. 703,715, dated July 1, 1902.

Application filed January 25, 1902. Serial No. 91,271. (No model.)

To all whom it may concern:

Be it known that I, OTTO WENTZEL, a citizen of the United States, residing at Jersey City, in the county of Hudson and State of 5 New Jersey, have invented certain new and useful Improvements in Safety Devices for Pin-Tongues, of which the following is a specification.

This invention relates to a safety device for 10 the pin-tongue of breastpins, badges, or similar articles, and has for its object to provide means for securely engaging the pin-tongue, so as to prevent the accidental unfastening of the same.

15 For this purpose the invention consists of a safety device for pin-tongues, comprising a tubular body having a perforated end, a bifurcated rest provided at said end, a rod housed in said body and projecting from the 20 perforated end thereof, a longitudinally-movable socket mounted on the projecting end of said rod, a spring engaging said rod, a pin-tongue pivoted to said tubular body, said movable socket adapted to engage the point 25 of said pin-tongue, as will be more fully described hereinafter and finally pointed out in the claims, reference being had to the accompanying drawings, in which—

Figure 1 is a side elevation of my safety device 30 that is adapted for use in breastpins, badges, or similar articles. Fig. 2 is a top view thereof. Fig. 3 is a vertical longitudinal section showing in dotted lines the parts in open position. Figs. 4 and 5 are respectively a side elevation and a vertical longitudinal section of the invention, showing the pin-tongue in open position; and Fig. 6 is a vertical transverse section on lines 66, Fig. 3.

Referring to the drawings, the safety device 40 for a pin-tongue that is adapted to be applied to breastpins, badges, or similar articles is composed of a tubular body A, the pin-tongue B, the spring-actuated socket C for receiving the end of the pin-tongue D, and the auxiliary securing means D, that additionally secures the pin-tongue from becoming unfastened.

The tubular body A is open at one end and is provided thereat with a longitudinal slot a, 45 that is flanked at its outer end by the lugs a', between which the pin-tongue is pivoted.

The opposite end of the tubular body A is provided with a central aperture a² and has arranged flush with its face the bifurcated rest or standard a³. The pin-tongue B is preferably secured in a mounting b, that is pivotally secured between the lugs a' and that is provided with the finger b', disposed parallel to the pin-tongue and adapted to pass into the longitudinal slot a of the tubular body when 6c the pin-tongue is depressed, so that the same can be engaged by the auxiliary securing device D.

The socket C is secured at its base c to the projecting end of the rod c', that is housed 65 in the tubular body A. At the inner end of the rod c' is provided the auxiliary securing device D, which consists of the plate d, that is supported and secured on the stud d', which latter is mounted on the end of the rod c' and 70 projects through the longitudinal slot a approximately midway between the ends of the same. Between the stud d' and the apertured end of the tubular body A is interposed around the rod c' the spring E, which retains 75 the socket C and the plate d in proper relation, respectively, to the point of the pin-tongue and to the finger b' when the same are in closed position.

The socket C is adapted to be pulled longitudinally in outward direction when it is desired to secure the pin-tongue, and the socket C is of a flaring shape, so as to facilitate grasping the same between the fingers. This action taking place against the compression-spring E moves simultaneously the plate d, so as to permit the finger b' to lower through the longitudinal slot of the tubular body and the pin-tongue to lower to the rest a³, when the pull that is exerted upon the socket is 80 released, so that the socket returns to its normal position under the action of the spring and engages the point of the pin-tongue and the plate d returns to its normal position, covering the slot a, so as to lock the finger 85 b' additionally to the socket C, engaging the pin-tongue.

Having thus described my invention, I claim as new and desire to secure by Letters Patent—

1. A safety device for pin-tongues, comprising a tubular body having a perforated

end, a bifurcated rest provided at said end, a rod housed in said tubular body and projecting from the perforated end thereof, a longitudinally-movable socket mounted on 5 the projecting end of said rod, a spring engaging said rod, and a pin-tongue pivoted to said tubular body, substantially as set forth.

2. A safety device for pin-tongues, comprising a tubular body having a longitudinal 10 slot at one end thereof, a pin-tongue pivoted to said end, a spring-actuated socket at the opposite end of said tubular body, a rod in said tubular body carrying said spring-actuated socket, a finger connected with said pin-tongue adjacent its pivotal point, and means 15 at the inner end of said rod for engaging said finger, substantially as set forth.

3. A safety device for pin-tongues, com-

prising a tubular body having a longitudinal slot at one end thereof, a mounting pivoted to said slotted end, a pin-tongue secured in said mounting and extending parallel to said pin-tongue, a rod housed in said tubular body, a spring-actuated socket mounted on the outer 20 end of said rod, a stud secured to the inner end of said rod, and a plate mounted on said stud, substantially as set forth.

In testimony that I claim the foregoing as my invention I have signed my name in presence of two subscribing witnesses.

OTTO WENTZEL.
